Assistant Examiner — Katherine A Holbrow

(57) **CLAIM**

The ornamental design for a display screen or portion thereof, with graphical user interface, as shown and described.

DESCRIPTION

FIG. 1 is a front view of a first embodiment of a display screen or portion thereof with graphical user interface, showing the new design; and, FIG. 2 is a second embodiment thereof. The dot-dash lines depict a display screen or portion thereof, and form no part of the claimed design.

1 Claim, 2 Drawing Sheets
